UNITED STATES PATENT OFFICE.

STEPHEN B. DOUSE, OF SALINA, KANSAS.

ELEVATOR-DOOR-OPERATING MEANS.

1,243,924.

Specification of Letters Patent. Patented Oct. 23, 1917.

Application filed May 29, 1917. Serial No. 171,679.

To all whom it may concern:

Be it known that I, STEPHEN B. DOUSE, a citizen of the United States, residing at Salina, in the county of Saline and State of Kansas, have invented certain new and useful Improvements in Elevator-Door-Operating Means; and I do declare the following to be a full, clear, and exact description of the invention, such as will enable others skilled in the art to which it appertains to make and use the same.

My invention relates more particularly to the automatic opening and closing of the doors leading from the several floors of buildings into the elevator shafts thereof, the object being to provide an extremely simple and inexpensive arrangement of parts for automatically opening the doors as the elevator car approaches the respective levels thereof and for then permitting said doors to close as the car moves above or below said levels.

With the foregoing general object in view, the invention resides in the novel features of construction and unique combinations of parts to be hereinafter fully described and claimed, the descriptive matter being supplemented by the accompanying drawing which forms a part of this specification and in which:

Figure 1 is a vertical section of an elevator shaft and a side elevation of an elevator therein, showing the application of the invention, one of the doors being illustrated in open position;

Fig. 2 is a view similar to Fig. 1 but illustrating the manner in which the door lifter is automatically released; and

Fig. 3 is a horizontal section on the plane of the line 3—3 showing one manner in which the lifter releasing cams may be mounted in the shaft.

In the drawing above briefly described, the numeral 1 has reference to an elevator shaft leading through the several floors 2 of a building, vertically sliding doors 3 being provided for normally closing the doorways 4 at the several floors. Preferably, though not necessarily, the doors 3 are provided with weights 5 connected thereto by cables 6 and substantially balancing said doors, the latter being slightly heavier than the weights, however, in order that they may close by gravity.

The lower edges of all the doors 3 with the exception of those at the extreme upper

and lower ends of the shaft, not shown, are provided with inwardly extending projections 7 adapted to be struck by a laterally projecting nose 8 on a door lifter 9 carried by the elevator car 10, said lifter being shown in the form of a vertically disposed lever fulcrumed between its ends to the car as shown at 11, the nose 8 being located above said fulcrum and a coiled spring 12 being connected with the lower end of the lever to normally so position the latter as to maintain said nose in projected operative position for contact with the projections 7 as the car ascends. A U-shaped stop 13 is provided with its arms in the path of the lower end of the lever 9 to limit the action of the spring and to prevent rocking of the lever an excessive amount as it engages the projections 7 and the cams, yet to be described, during the descent of the car.

The upper end of lever 9 is provided with a laterally extending shoe 14 for engagement with a vertical cam 15 mounted in the shaft 1 in any preferred manner, it being the office of said cam and shoe to so shift the lever 9 as to retract its nose 8 from the projection 7 as the car 10 rises above the level of the door which has previously been opened by said nose.

In operation, as the elevator ascends, the nose 8 will strike the projections 7 of the several doors and will thus successively open said doors and hold them in open position until the car rises above the level thereof. When this takes place, however, the adjacent cam 15 and the shoe 14 coact to release said nose 8 from engagement with the door, whereupon the latter lowers by gravity. When the car is descending, the shoe 14 and cam 15 rock the lever 9 to an inoperative position and thus prevent the nose 8 from contacting with the projections 7. It is necessary for the car to be traveling upwardly before any of the doors, with the exception of the lowermost (not shown) can be opened thereby.

From the foregoing, taken in connection with the accompanying drawing, it will be obvious that although the invention is of simple and inexpensive nature, it will be highly efficient and will well perform the functions for which it is designed. In fact, the particular construction shown and described has been for several months in actual use and is proving satisfactory in all respects. On account of its proven merit,

2
this construction constitutes the preferred form of the improved operating means, but it is to be understood that within the scope of the invention as claimed, numerous minor changes may be made without sacrificing the principal advantages.

I claim:

In combination, an elevator, shaft, an elevator car mounted in said shaft, an upwardly opening door from said shaft having a projection extending into said shaft, a vertical lever fulcrumed between its ends on one side of the car and having above its fulcrum an upwardly facing shoulder formed on its front edge for engagement with the lower side of said projection when the car ascends, the front edge of said lever inclining upwardly and outwardly to said

shoulder for free sliding over said projection when the car descends, a spring connected to the lower end of the lever for moving it to operative position, a laterally extending vertically disposed shoe carried by said lever above its fulcrum and beveled at both its upper and lower ends, and a vertically elongated cam fixed in the elevator shaft for engagement with said shoe to release said shoulder from engagement with said projection.

In testimony whereof I have hereunto set my hand in the presence of two subscribing witnesses.

STEPHEN B. DOUSE.
